UNITED STATES PATENT OFFICE.

JOHN SAWICKI, OF IRONWOOD, MICHIGAN, ASSIGNOR OF ONE-FOURTH TO ISAAC J. WATSON AND ONE-FOURTH TO FRANK MICHELL, BOTH OF IRONWOOD, MICHIGAN.

RAILWAY GATE.

Application filed September 21, 1922. Serial No. 589,621.

To all whom it may concern:

Be it known that I, JOHN SAWICKI, a citizen of Poland, residing at Ironwood, in the county of Gogebic and State of 5 Michigan, have invented certain new and useful Improvements in Railway Gates, of which the following is a specification.

The present invention relates to useful improvements in railway gates, and has for 10 its primary object thereof the provision of such a railway gate that will be wholly automatic in its operation so as not to require the attention of a gateman, the same being always positive in its operation.

15 A further object of this invention is the provision of a railway gate wherein the same is adapted to be operated by means positioned at a distant point upon the rails of the trackway for actuation by the wheels 20 of the train engaging therewith.

A still further object of the invention is the provision of a railway gate that is comparatively simple in its construction and operation and such a gate that when once 25 installed is not liable to readily become out of order.

With the above and other objects of the invention in view as the nature thereof will be better understood, the same consists of 30 the novel form, combination and arrangement of parts hereinafter more fully described, shown in the accompany drawing and claimed.

In the drawing, wherein like reference 35 characters designate corresponding parts throughout the several views,

Figure 1 is a top plan view of a section of a railway track showing my device applied thereto at a highway crossing,

40 Figure 2 is an enlarged, fragmentary vertical longitudinal sectional view of a portion of the structure, one of the gates being shown as removed from its support,

Figure 3 is a transverse cross sectional 45 view upon the lines III—III of Fig. 1,

Figure 4 is a vertical cross sectional view of the actuating mechanism for the several gate members and being taken upon the lines IV—IV of Fig. 6,

50 Figure 5 is a view similar to Fig. 4 taken upon the lines V—V of the same figure,

Figure 6 is a vertical cross sectional view of the structure shown in Figs. 4 and 5, a portion of the device being shown in elevation, and

Figure 7 is a perspective view of the dog carrying member for actuating the mechanism controlling the movement of the gates.

Referring more in particular to the several views, there is shown in Fig. 1 a section of trackway comprising the usual spaced rails 1 and 2. In this figure the section of trackway is shown as having a road 3 extending thereacross, and upon each side of this road and outwardly of each of the rails 1 and 2 are pivoted gate members 4 adapted to swing inwardly toward each other to extend parallel with the tracks and at a distance thereabove for effectively closing the roadway and preventing passage across the tracks. These gates 4 are of any desired form, and are pivoted within vertically disposed hollow metallic post members 5 as at 4'. In the preferred embodiment of my invention, however, these 75 swinging gate members are shown as comprising spaced strips 6 and 7, being joined together for a portion of their length and upon the rear edges thereof by a cross webbing 8. The rear walls of each of the post 80 members 5 are cut away for a greater portion of their length as at 9 for permitting the entrance of the adjacent portion of the gates to swing into and out of the post, the front walls of these posts being likewise 85 cut away for a portion of their length as at 10 for purposes similar to the cutouts 9. The hollow gate receiving posts upon opposite sides of the roadway are so disposed as to allow the spaced fingers 6 and 7 comprising the gate members 4 to interengage 90 with each other, it being clearly noted that when these gate members are in their open positions the same will extend vertically within their posts and when swung to their 95 closed position will extend horizontally across the roadway.

The post members 5 have enlarged base portions 11 having formed upon their lower edges a marginal flange 12 for securely anchoring these enlarged portions of the post beneath the surface of the ground. These base members 11 of the post 5 upon one side of the roadway 3 establishing communication with the similar base members of 105 the post upon the same side of the roadway and across the track section, for purposes hereinafter more fully described. In Fig. 3 the post members upon one side of the roadway are shown as being interconnected 110

by a housing 13 formed as an integral part of the base portions 11.

Upon the pivots 4' for each of the post members and between side legs 6 and 7 thereof is keyed or otherwise secured thereto a sprocket gear 14 having a sprocket chain 15 associated therewith adapted to engage over a similar sprocket gear 16 keyed to a shaft 17 slightly inwardly of the outer ends thereof, the extreme ends of this shaft being supported within bearing members 18 formed within the housing 13, it being noted that these shafts extend in a longitudinal direction through each of the housings 13.

15. At a distant point upon the rail 1 of the trackway and at each side of the cross road 3 there is secured a box-shaped housing 19 having a shaft 20 journaled therethrough upon which is keyed a sprocket gear 21 for receiving a sprocket chain 22. These sprocket chains 22 extend parallel with the track 1 and engage over at their opposite ends, a similar sprocket wheel 23 upon each of the shafts 17 within the housings 13 for 25 rotating these shafts when the sprocket gears 21 are rotated for consequently imparting a swinging movement to each of the gate members 4. As shown in Figs. 2 and 3, each of the housings 13 are suitably slotted as at 24 30 for permitting the entrance of the sprocket chains 22 thereinto.

As a means for controlling the rotary movement of the sprocket wheel 21 on the shaft 20 in opposite directions, there is keyed to this shaft 20 two ratchet wheels 25 and 26 in close contact with each other. These ratchet wheels are spaced from the sprocket wheel 21 by a spacing wall 27 formed between the side walls of the housing 19. As 40 shown in Figs. 4, 5 and 6, these ratchet wheels are provided with ratchet teeth upon only one-half of their periphery, the remaining half of each of the wheels being left plain and it being noted that the ratchet 45 surface of the outer wheel 25 is adjacent the plain surface of the other wheel 26, the teeth upon the wheel 26 being adjacent the plain surface of the wheel 25 for purposes herein-after described. Loosely positioned upon 50 the shaft 20 between the ratchet wheel 26 and the adjacent surface of the inner wall of the housing 19 is a swinging dog carrying member 27 notched upon its opposite sides and adjacent its lower end as at 28 for 55 receiving the ends of leaf springs 29 bolted or otherwise secured to the adjacent walls of the housing. By the provision of the leaf springs 29 the dog carrying member 27 will normally assume a position as shown in full 60 lines in Figs. 4, 5 and 6. This member 27 is shouldered at its upper end as at 30 which shouldered portion overlies the ratchet wheels 25 and 26 and has pivotally secured thereto at the opposite sides thereof dog 65 members 31 and 32 so positioned as to en-

gage with the ratchet wheels 25 and 26 when the member 27 is swung in opposite directions. These dog members are normally maintained out of engagement with their respective ratchet wheel by the medium of 70 springs 33 carried by the shouldered end of the member 27. Disposed upon the side walls of the box members 19 and adjacent the lower ends of the dogs 31 and 32 are other flat curved spring members 34 for 75 guiding the respective dog member into engagement with its ratchet wheel when the swinging dog carrying member 27 is swung in a direction toward either one of these springs.

The upper end of the dog carrying plate 27 has formed thereon spaced ears 35 for revolubly receiving therebetween a car wheel engaging roller 36. Each of the box-like housings 19 are so positioned inwardly of the rail 1 as to allow this roller member 36 upon the dog carrying member 27 to lie adjacent the thread of the rail and to project a slight distance thereabove, whereby due to the passing of the train over the 90 rails 1 and 2 the wheels upon one side thereof will successively engage the roller 36 for actuating the shaft 20 within the housing 19 and for consequently controlling the swinging movements of the pivoted gate 95 members 4.

The operation of my invention is as follows:—

The box like members 19 with their associate mechanism being disposed at a distant point upon the trackway at both sides of the road crossing 3 it will be readily understood that a train coming toward either one of these housings 19, the wheels thereof will successively engage the roller 36 of the 100 dog member 27 for intermittently swinging the same from its substantially central vertical position to a position as shown in dotted lines in Fig. 4 for consequently engaging the dog member 32 with its associate ratchet wheel for rotating the shaft 20 and for consequently rotating the shaft 105 13 through the medium of the sprocket and chain connections therebetween, for consequently closing the gates upon both sides of 110 the roadway. As before stated the ratchet teeth upon each of the wheels extend only around one-half of the periphery thereof, it being readily understood that the gearing is such as to allow the gates to be fully 115 closed when either of the ratchet wheels 25 or 26 have made one-half of a revolution, it being further noted that when the gates are fully closed the plain surface of the ratchet wheel being actuated by either of the 120 dogs 31 and 32, will be brought into engagement with its respective dog thereby preventing any further rotation of the shaft 20 even though the dog carrying member 125 27 is being actuated by other wheels of the 130

train upon the track section. As soon as the train has crossed over the road crossing 3, and the wheels thereof successively engage the roller 36 of the dog member 27 in the 5 other housing 19 upon this side of the roadway, the dog carrying member will be so actuated as to have one of the dogs thereof ratchet upon its respective ratchet wheel for rotating the shaft 20, and for consequently 10 rotating the shaft 13 in an opposite direction for extending the gates 4 to an open position. Each of the shafts 17 have a pulley wheel 35, keyed or otherwise secured thereon, for receiving an endless belt 36 15 therebetween, this belt 36 being shown as crossed whereby movement of the gates at one side of the roadway to a closed position will occasion a similar movement to the gates upon the opposite side of the roadway. 20 While there is herein shown and described the preferred embodiment of the present invention, it is nevertheless to be understood that minor changes may be made therein without departing from the spirit and scope 25 thereof as claimed.

What is claimed as new is:—

In a railway gate, the combination with the posts and arms pivoted thereto on oppo-

site sides of a railway track and of the roadway crossing said track, of a shaft connecting the arms in the two posts located on the same side of the roadway on opposite sides of said track through the medium of sprocket and chain connections between the arms and shaft, means positioned at a distant 30 point upon the said track from the said roadway for actuating the said arms, said means comprising an arm member positioned adjacent one of the rails of the said track for engagement with the wheels of a train 35 passing over said track, said arm member being loosely positioned upon a shaft and having oppositely extending dog members pivoted thereto, a ratchet wheel keyed to said shaft beneath each of the dog members and having the teeth thereof extending in opposite directions, each of said dog members adapted for engagement with its adjacent ratchet wheel when the arm member is swung in opposite directions for opening or closing the gates, and connecting 40 means between the said ratchet wheel carrying shaft and the shaft between the said arm members.

In testimony whereof I affix my signature. 45
JOHN SAWICKI.
